APPARATUS FOR RECLAIMING FINE
(FLOUR) GOLD FROM CONCENTRATESWalter M. Caughlan, Denver, Colo., assignor of
one-half to O. N. Rounsvell, Littleton, Colo.,
and one-half to Irving Lindner, Denver, Colo.

Application November 30, 1934, Serial No. 755,482

4 Claims. (Cl. 209—205)

This invention relates to certain new and useful improvements in apparatus for reclaiming fine (flour) gold from concentrates.

The primary object of this invention is to provide apparatus for the extraction of fine gold from placer ground, crusher concentrates and the like and particularly tailings from other machines embodying a plurality of juxta-posed cells arranged at an inclination with means in each cell for agitating and cutting the material and for conveying suspended material to a succeeding cell with the fine gold extracted from the material settling into a mercury cup removably attached to the lower end of the cell.

A further object of the invention is to provide apparatus of the foregoing character with a vibrating arm in the settling chamber or cup of each cell to be operated by the cutter and material that is rotatably mounted in the cell for the agitation of the material at the lower end of the cell to effect the settling of gold flour and the flotation of dirt etc., and any entrained gold flour for delivery to the succeeding cell.

With the above and other objects in view that will become apparent as the nature of the invention is better understood, the same consists in the novel form, combination and arrangement of parts hereinafter more fully described, shown in the accompanying drawings and claimed.

In the drawings:—

Figure 1 is a top plan view of the apparatus for reclaiming fine gold and illustrating a series of cells with inter-geared ground working devices in each cell;

Figure 2 is a side elevational view showing the apparatus arranged at an inclination with a washing screen fragmentarily illustrated above the apparatus;

Figure 3 is a fragmentary longitudinal sectional view showing the juxta-posed communicating cells and the devices for cutting, agitating and feeding the material to a succeeding cell;

Figure 4 is a fragmentary detail sectional view of the lower end of one cell, showing a vibrating arm therein;

Figure 5 is a cross-sectional view through one of the cells, showing the drive axle for the support of the material working elements with the latter removed; and

Figure 6 is a fragmentary top plan view showing a series of cells with the material working elements removed.

Referring more in detail to the accompanying drawings, the apparatus embodies a pair of side

irons or bars 10 between which a plurality of cells 11 are suitably secured. Each cell is of semi-circular formation in cross-section with adjacent edges of the cells contacting, or formed integral with each other as illustrated in Fig. 3. 5 A pair of guide ribs 12 is carried by the upper face of each cell at the forward side thereof that diverge from the center of the bottom of the cell to the forward corner and the bottom of the cell is transversely grooved as at 13 for directing material, such as gold powder or the like into the sump 14 centrally of the bottom of the cell. The lower end of the stub 14 is exteriorly threaded for the reception of the cup-shaped cap 15 having a sealing gasket 16 therein and said sump is adapted to contain a desired quantity of mercury as indicated at 17 for the collection of gold powder or the like separated from the earthy material.

A rotary screen 18 is arranged above the cells 11 for the washing and grading of material to be delivered to one end cell of the series, and this screen and feed hoppers therefore constitute no part of the present invention.

The frame structure supporting the cells 11 is arranged at an inclination as illustrated in Fig. 2, the lower end of the frame structure having a foot plate 19 pivotally attached thereto as at 20 while the elevated end of the frame structure carries an elevating screw 21 pivoted there-to as at 21' and working in the screw block 22 carried by the stand 23. By adjusting the screw 21, the inclination of the frame structure carrying the cells is regulated and the speed of flow or delivery of the material through the apparatus is likewise controlled by the degree of inclination of the frame structure.

Means is provided in each cell to act on the material received therein and includes agitator members, a cutter device for disintegrating the material and a feed device or lifter for conveying the material to the succeeding cell. As shown more clearly in Figs. 1, 3 and 5, each cell has a shaft 24 journaled through the side walls thereof and rotatable in bearings 25 and 26 supported on the side bars 10 outwardly of the cells and upon which shafts, the earth-working devices are mounted. A collar 27 as shown in Figs. 3 and 5 that is hexagonal in cross-section is fixed to the shaft 24 by means of anchor devices, such as screws threaded in openings 28 in the collar 27 for engagement with the shaft 24. However, it is to be understood that relatively short collars or bearings may support the earth working elements on the shaft 24 in view 55

of the full length of collar 27 shown in Figure 5. The earth working devices of any desired number are secured to the facets of the hexagonal collar 27 and as shown in Figures 1 and 3, a cutting blade including a base strip 29 is suitably anchored to a facet of the collar 27 and carrying a series of cutting blades 30 with a centrally positioned trip arm 31. A material conveying or lifting device for delivering the material to the succeeding cell is secured to a facet of the collar, substantially opposite the cutter member and is in the form of a plate 32 angularly bent lengthwise thereof as at 33 and 34 to provide a pocket 35 at one side for the reception of material delivered thereto from the preceding cell and a lift face 36 at the other side for conveying the material to the succeeding cell, the relative positions of two lift plates in adjacent cells at the time of delivery and reception being illustrated in Figure 3. A pair of agitators is secured to the collar 27, one at each side of the cutter blade and each agitator includes a base strip 37 having twisted arms 38 projecting therefrom for the agitation of the material delivered to the cell 11.

Blades are added and the incline raised or lowered for handling different types of gold, the coarse gold requiring more blades and lower incline.

A resilient vibrating arm 39 is anchored at its lower end as at 40 in the sump 14 of the cell and projects upwardly through the sump into the lower end of the cell to be engaged at its upper end by the trip arm 31 of the cutter at the outer edge of the lift plate 32 for the agitation of material at the lower end of the cell for the more effective separation of gold therefrom.

The shafts 24 carrying the earth working devices are synchronously driven to cause the lift arms 32 to assume the relative positions shown in Fig. 3 with respect to adjacent edges of the cells 11 and as shown in Fig. 2, each shaft 24 carries a gear wheel 41 on the projecting end thereof adjacent the shaft bearing 26 with a pinion 42 disposed between adjacent gears 41 to cause all of said shafts to rotate in the same direction as indicated by the arrow line 43 in Fig. 3. Power may be applied to any one of the shafts 24 for the simultaneous operation of all of said shafts.

When the frame structure carrying the cells is inclined as shown in Figs. 2 and 3, the forward edge of each cell is higher than the rear edge and each cell is filled with water to the level of the rear edge thereof. The material to be treated is delivered into the lower cell 11a shown in Fig. 2 and is worked upon by the agitators and cutters in said cell, the vibrating arm 39 also effecting agitation of the material at the lower end of the cell. The outer edges of the agitators, cutting blades and lifter blades move in proximity of the inclined ribs 12 for further disintegration and agitation of the material, the gold dust and particles separated therefrom being precipitated into the sump 14 for collection in the mercury 17. The lift plate 32 rotates in a direction to cause the lift face 36 thereof to move the material upwardly in the first cell for discharge over the forward edge thereof into the pocket side 35 of the lift arms in the succeeding cell as shown in Fig. 3, where the material is treated in a similar manner and later delivered by the lift face of the lift plate into the succeeding cell 11. Each cup-shaped cap 15 is removable from the sump 14

for the extraction of the gold from the mercury therein. It is to be noted that the apparatus operates in quiet water and the feed of material is due to lifters. As stated, the ore is taken into the first cell, dropping upon the back of the lifter into the cell filled to a certain level with water. The gold being heavier, drops faster and reaches the grooved lower part of the cell. The material is then acted upon by the first row of agitators which stir up the sediment, gold etc., and which tend to float the materials other than gold into the next cell along with a decreased amount of gold not taken up by the mercury in the sump of the first cell. The material is then acted upon by the cutters which act to disintegrate the material and the third row of agitators tends to whirl the material and sediment in the opposite direction from that set up by the first series of agitators. Then the lifter blade lifts the material and sediment to the next cell and deposits it upon the pocket face 35 of the succeeding lifter blade in the next cell. The sediment and the gold are worked up-hill under quiet water and no force or gravity feed or action is utilized. For the finest gold, the incline is increased, thus working the ore through the machine slower than when the incline is nearer level. The tailings are discharged from the apparatus at the point 44 shown in Figure 2.

It is difficult to operate with less than six cells, ten being preferable, and the number of turns per minute should be 18 (due to the weight of gold).

From the above detailed description of the invention, it is believed that the construction and operation thereof will at once be apparent and while there is herein shown and described the preferred embodiment of the invention, it is nevertheless to be understood that minor changes may be made therein without departing from the spirit and scope of the invention as claimed.

I claim:—

1. In gold mining apparatus, a series of cells arranged at an inclination and communicating at their adjacent upper edges, independent means in each cell for effecting agitation, disintegration and feeding of material into a succeeding cell, and means for synchronously operating the means in the cells, the feeding means in each cell including a blade angularly bent lengthwise thereof to provide a receiving pocket for material from a preceding cell and a lifting face for feeding material to a succeeding cell, and a vibrator arm at the lower end of each cell to be engaged by the disintegrating and feeding means.

2. In gold mining apparatus, a series of cells arranged at an inclination and communicating at their adjacent upper edges, independent means in each cell for effecting agitation, disintegration and feeding of material into a succeeding cell, and means for synchronously operating the means in the cell, a sump at the lower end of each cell and a mercury cup closing the lower end of each sump, the feeding means in each cell including a blade angularly bent lengthwise thereof to provide a receiving pocket for material from a preceding cell and a lifting face for feeding material to a succeeding cell, and a vibrator arm at the lower end of each cell to be engaged by the disintegrating and feeding means.

3. In gold mining apparatus, a series of cells arranged at an inclination and communicating at their adjacent upper edges, independent means

in each cell for effecting agitation, disintegration and feeding of material into a succeeding cell, and means for synchronously operating the means in the cells, the feeding means in each 5 cell including a blade angularly bent lengthwise thereof to provide a receiving pocket for material from a preceding cell and a lifting face for feeding material to a succeeding cell, a shaft in each cell supporting the means therein and the operating means including meshing gears 10 and pinions interposed between the several shafts and geared to present the free edges of the feed blades simultaneously at adjacent edges of two cells for the delivery and reception of material, 15 and a vibrator arm at the lower end of each cell to be engaged by the disintegrating and feeding means.

4. In gold mining apparatus, a series of cells arranged at an inclination and communicating 20 at their adjacent upper edges, independent means

in each cell for effecting agitation, disintegration and feeding of material into a succeeding cell, and means for synchronously operating the means in the cell, a sump at the lower end of each cell and a mercury cup closing the lower 5 end of each sump, the feeding means in each cell including a blade angularly bent lengthwise thereof to provide a receiving pocket for material from a preceding cell and a lifting face for feeding material to a succeeding cell, a 10 shaft in each cell supporting the means therein and the operating means including meshing gears and pinions interposed between the several shafts and geared to present the free edges of the feed blades simultaneously at adjacent edges 15 of two cells for the delivery and reception of material, and a vibrator arm at the lower end of each cell to be engaged by the disintegrating and feeding means.
